UNITED STATES PATENT OFFICE.

CHARLES EDWARD FANNING, OF DAVENPORT, IOWA, ASSIGNOR OF ONE-HALF TO H. C. FIRST, OF MOLINE, ILLINOIS.

AUTOMATIC TRAIN-OPERATED RAILWAY-GATE.

No. 828,808.

Specification of Letters Patent.

Patented Aug. 14, 1906.

Application filed December 27, 1905. Serial No. 293,503.

To all whom it may concern.

Be it known that I, CHARLES EDWARD FANNING, a citizen of the United States, residing at Davenport, in the county of Scott and State of Iowa, have invented certain new and useful Improvements in Automatic Train-Operated Railway-Gates; and I do hereby declare the following to be a full, clear, and exact description of the invention, such as will enable others skilled in the art to which it appertains to make and use the same.

The object of this invention is to provide practicable and effective mechanism for automatically operating railway-gates by the passing train wherein the actuating machinery connected with the gates is not positively connected with the parts which are immediately actuated by the train, thus avoiding all effect of impact, sudden strains, or shocks upon the gates, the gate-operating mechanism, and their connecting-cables.

Without limitation to the specific embodiment illustrated, which is susceptible of modification in details of construction and arrangement of parts, the invention will be fully described by reference to the accompanying drawings, which constitute a part of this specification, and will then be more particularly defined and pointed out in the appended claims.

In said drawings, Figure 1 is a diagrammatic plan view of the railway and grade-crossing equipped with railway-gates and automatic gate-operating apparatus embodying my invention. In this diagrammatic figure the railway-gates C C' and also the gate-actuating mechanisms F F', which in reality stand upright or vertical, are represented as if turned over to horizontal positions, thus appearing in side elevation, which is for the purpose of clearer illustration. Fig. 2 is an enlarged perspective view of the gates and gate mechanism. Fig. 3 is an enlarged perspective view of one of the gate-actuating mechanisms, it being understood that there are two of such mechanisms, one at each side of the grade-crossing and at a suitable distance therefrom. Fig. 4 is an end elevation of one of the gate-actuating mechanisms. Fig. 5 is a top plan view thereof. Fig. 6 is a vertical section of the same, taken on line VI VI of Fig. 5, with parts in front elevation.

A particular description of the illustrated apparatus is as follows:

The railway A is crossed by the road or street B. In this illustration the crossing is protected by two gates C C' at opposite sides of the track. These are suitably connected to operate in unison or to fall and rise together. For this purpose the gate mechanism is shown comprising an underground cross rod or axle D, having rigid pulleys or sprockets D' at its opposite ends, which are connected by endless bands, cables, or sprocket-chains D² with pulleys or sprockets, D³, fast with the pivots or axles of the gates themselves. By turning the cross-rod the gates close and open or fall and rise together, so that operation directly upon one gate will transmit a corresponding motion to the opposite gate. At each side of the track angularly-related rocker-arms E and E' are mounted fast with the cross-rod or axle D, the same being shown affixed on the pulleys D', and to these rocker-arms are connected the cables which lead to the gate-actuating mechanisms. Said gate-actuating mechanisms F and F' are located at opposite sides of the road-crossing, each at a suitable distance therefrom, and are adapted to be actuated by the passing train. The train in approaching the crossing actuates the first mechanism to close or lower the gates and when leaving the crossing actuates the second mechanism to open or raise the gates to their normal position. These two mechanisms F and F' are respectively connected with the gate mechanism by "cables" G and G', which term includes ropes, chains, wires, or other appropriate flexible connections. By means of said cables G and G' extending from both gate-actuating mechanisms along both sides of the track the gate-actuating mechanisms are also connected with each other. As shown, the cables G G' at one side of the track (here the left-hand side) pass under guide-pulleys G² directly to the rocker-arms E' E, respectively, to which said cables are attached, whereas the cables G G' at the opposite side of the track (here the right-hand side) are carried past each other beyond the gate C, under similar guide-pulleys G², and thence backwardly to the rocker-arms E E', so that the cables at one side of the track are connected to the rocker-arms in a reverse

manner with respect to the connections of the cables and rocker-arms at the opposite side. This arrangement allows longitudinal movement of the cables at one side of the 5 track in a direction opposite to the longitudinal movement of the cables at the other side for a purpose hereinafter appearing.

Both mechanisms F and F' being similar, a description of one will suffice. Attention 10 is directed for the moment to the mechanism F, referring particularly to Figs. 3, 4, 5, and 6. This mechanism, supported in a relatively long and narrow frame H, is arranged beneath the track and transversely of the 15 same. At the opposite upper ends of the frame H are fulcrumed or pivoted two levers I and I'. These are disposed approximately horizontal and are adapted to rock or oscillate vertically. Their inner ends overlap 20 side by side and are shown having L-shaped parts whose innermost arms J are in alignment, considered longitudinally of the track. Said levers I and I' rest, respectively, upon the upper shorter arms of two intermediate- 25 fulcrumed levers K and K'. These lower levers K K', fulcrumed at the upper part of the frame H, are in this instance shown with their longer arms crossing. They are arranged approximately vertically and 30 are adapted to swing or oscillate transversely of the track.

Above the alined parts J of levers I and I' there is an upright cam L or rocker-arm or 35 tilting member projecting above the track and serving as a trip for engagement by a part carried by the passing locomotive, and in this connection it may be stated that in conjunction with this invention the locomotives of the line are to be equipped with 40 some appropriate actuator—such as a roller, cam, or projection—preferably depending from the bottom of the locomotive for striking or engaging the cam or rocker-arm L. Said cam or rocker-arm L is the medial mem- 45 ber of a triarmed or T-shaped lever L', medially fulcrumed and arranged longitudinally of the track with its horizontal lever-arms either resting upon or adapted to bear upon the said alined parts J. As the cam or 50 medial rocker-arm L is rocked one way or the other, according to the direction of travel of the train and according to which side of said cam is struck by the locomotive's actuator, said horizontal lever L' will bear down upon 55 and depress either one or the other parts J, thus depressing either lever I or lever I', as the case may be, and this movement swings up the lever K or the lever K' accordingly, thereby actuating other parts now to be de- 60 scribed.

At the bottom of the frame H, beneath the cam L and its associated parts, there is a stationary block M. Inclined rods N connect this block with the opposite upper ends of 65 the frame. Said rods N constitute slides or

guideways for heavy weights, two at each side of the central block M and designated, respectively, O P and O' P'. The lower weights O and O' are free and disconnected, while the upper weights P and P' are respectively connected with the cables G at the opposite sides of the track, the weight P at the right being connected with the cable running to the right-hand gate C and the weight P' at the left being connected with the cable 70 running to the left-hand gate C'. It may be noted in passing that the weight P practically balances the weight P' at the opposite side of the apparatus, since these two weights are connected to the opposite ends of 75 the same flexible connection—namely, to the ends of the cables G G, which work oppositely—and are connected together by the gate mechanism D, E, and E', as before explained. Therefore weights P and P' should 80 be substantially equal. Weights O and O' should also be substantially equal. In normal position of the apparatus—that is, when the railway-gates are open or raised—the upper weight P at the right-hand side of the 85 central block M is up, while the three remaining weights P', O, and O' are down. Each lower weight O or O' is adapted when lifted up and released to engage and drag down by gravity its associated upper weight 90 P or P'; but there is no engagement or connection between the two weights O P or O' P' when either pair is down. For this purpose one of each pair of weights, in this case the two upper weights P P', are equipped with 95 hooks Q, which are adapted to engage lateral pins or projections Q' on the other weights (here the lower ones O and O') whenever one of the lower weights is lifted up to a previously-raised upper weight; but whenever 100 both weights of one pair O P or O' P' are down there is no connection between them, which is accomplished in this instance by having the hooks Q ride up on the block M 105 out of engagement with the pins Q', thus unhooking themselves. Hence should an upper weight be down, as seen at the left of Figs. 3 and 6, it is free to rise when pulled up by its cable without dragging up its lower weight, the purpose of all of which will 110 appear later. The lower weights O and O' are adapted to be lifted by the levers K and K', respectively, which levers are shown having 115 their lower ends extending under said weights.

So much for the nearest mechanism F. The farmost mechanism F', at the opposite side of the road-crossing, is of similar construction, but set oppositely or in a reversed position with respect to the mechanism F. 120 For example, in the normal position of the apparatus, where the raised upper weight P is at the right-hand side in the mechanism F, the corresponding raised weight P is at the left-hand side of the mechanism F', and 125 130

whereas in the mechanism F weights P P' are connected by their cables with the gates C C', respectively, in the mechanism F' the weights P P' are connected with the gates C' C, respectively.

In the normal position of the apparatus the parts of the mechanism maintain the relative positions shown in the diagrammatic Fig. 1. The gates C C' are open or raised to 10 permit free travel of wagons or teams across the track. The weights P of each gate-actuating mechanism are raised, while the other weights O, O', and P' are down. By virtue of the cable connections the mechanisms F and F' balance each other, and in each mechanism the weight P balances the weight P'. 15

It is desirable, also, that the gates themselves should be balanced on their pivots to avoid the effect of the weight of the gates 20 and cause them to fall and rise easily under the action of the gate-actuating mechanisms.

The operation is as follows: Assuming that a train is approaching the crossing toward the 25 nearmost mechanism F or in the direction of the arrows in the drawings, the locomotive, which is equipped with a depending roller, projection, or other actuator for the purpose, strikes the cam or rocker-arm L of said mechanism in such a direction as to depress 30 lever I, thereby swinging up lever K and lifting the weight O. Said weight O being thus forcibly lifted up against the weight P is caught by the hooks Q. The weight O now being added to the weight P pulls down the 35 latter weight by gravity, and thereby closes or lowers the gates. Simultaneously the corresponding weight P of the farmost mechanism F' is let down by the slackening or paying in of its cable, while both weights P' in 40 both mechanisms are dragged up by the shortening of their cables. Thus the effective work is performed by the weight O in the mechanism F. The gates are now closed or shut down. After the train passes the crossing, approaching the farmost mechanism F', 45

the locomotive's actuator strikes the cam or rocker-arm L of said mechanism F' in the same direction, thus depressing lever I', thereby swinging up lever K' and lifting the 50 weight O' up to the weight P', which weight P' has already been raised by the operation of the mechanism F. In said mechanism F' weight O' being added to the weight P' drags down the latter, thereby opening or 55 raising the gates, leaving the roadway clear and unobstructed over the track, as before. Simultaneously the corresponding weight P' of mechanism F is lowered, while the weights P of both mechanisms F and F' are returned 60 to their normal elevated positions. The position of the whole apparatus after the train has passed the crossing is the same as before. Now suppose the train approaches the crossing from the opposite direction. In this 65 case the locomotive passes first over the

mechanism F', and the locomotive's actuator strikes the cam or rocker-arm L in an opposite direction to that previously described, thereby depressing lever I, swinging up lever K, lifting weight O, and dragging down 70 weight P, and thereby closing the gates in the same manner as when the train closes the gates by passing over the mechanism F. Simultaneously the weights in both mechanisms adjust themselves in the same manner 75 as before described, so that when the train leaves the crossing by passing over mechanism F it actuates said latter mechanism to open the gates, leaving the whole apparatus in the same normal position as before described. 80

It will be observed that each mechanism F and F' comprises two sets of parts—first, the machinery which is immediately actuated by the passing train, and, second, the machinery 85 which is connected by the cables with the gate mechanism. These two sets of machinery are distinct and disconnected, so that the impact or blow of the train has no effect upon the gates, the gate mechanism, 90 the cables, nor the machinery directly connected with the gate mechanism. The only effect of the impact of the train or the actuator carried by the locomotive is to throw up one block or weight, which attaches itself to 95 the suspended block or weight, thereby overbalancing the weight of the gates and operating the same. All mechanism connected with the gates is thus entirely disconnected from the mechanism which receives the impact of the locomotive's actuator, so that the operation of this apparatus is smooth and easy at all times and there is no liability of transmitting shocks, jars, and sudden strains to the mechanism connected with the gates, 100 all of which is a most important point of the invention. The apparatus can be so adjusted as to make its operation relatively fast or slow, as desired, by adding to or taking from the weight of the working blocks. 105

In the appended claims, except when otherwise distinctly recited, the term "gate mechanism" shall be construed to designate a mechanism comprising or including a gate or gates having means for closing and opening a 110 railway-crossing, the term "extreme position" thereof shall mean either open or closed position of the gates, the term "gate-actuating mechanism" shall be construed to designate a mechanism adapted to be actuated by the 115 train for operating the gates, and the term "cable" shall be construed, either in the singular or plural, to designate appropriate motion-transmitting connections between said gate-actuating mechanism and said gate 120 mechanism. 125

Having thus fully described my invention, what I claim as new, and desire to secure by Letters Patent of the United States, is—

1. In an automatic train-operated railway- 130

gate, the combination of a gate mechanism and a gate-actuating mechanism located at a distance therefrom, the latter comprising an instrumentality connected by cable with said gate mechanism, and an independent disconnected instrumentality adapted to be actuated by the passing train, with means whereby the second-named instrumentality, after completion of motion under impact of the train, actuates said first-named instrumentality to pull the cable and thereby operate the gate mechanism.

2. In an automatic train-operated railway-gate, the combination of a gate mechanism and a gate-actuating mechanism located at a distance therefrom, the latter comprising an instrumentality connected by cable with said gate mechanism adapted when actuated to pull said cable, and an instrumentality adapted to be actuated by the passing train and including a weight which is raised thereby and then descends by gravity, with means for utilizing the force of the descending weight in actuating said first-named instrumentality.

3. In an automatic train-operated railway-gate, the combination of a gate mechanism, a gate-actuating mechanism located at a distance therefrom, and a connecting-cable, said gate-actuating mechanism comprising a weight suspended by said cable, a disconnected weight, and an instrumentality adapted to be actuated by the passing train for lifting the second weight which then descends by gravity, with means for connecting the two weights during such descent, thereby dragging down the first weight.

4. In an automatic train-operated railway-gate, the combination of a gate mechanism, distantly-located gate-actuating mechanisms at opposite sides thereof, each adapted to be actuated by the passing train, and cables connecting said gate mechanism with the respective gate-actuating mechanisms, the cables being thus in connection with each other, weights suspended at the opposite ends of these connected cables and in balanced relation, one weight being raised and the other lowered in either extreme position of the gate mechanism, lower disconnected weights associated with said suspended upper weights and each adapted to be raised by the respective gate-actuating mechanism as the train passes thereover, with means for connecting each lower weight when raised with its associated upper weight to cause the gravitation or fall of both weights, whereby the gate mechanism is operated in opposite directions as the train passes successively over the two gate-actuating mechanisms.

5. In an automatic train-operated railway-gate, the combination of a gate mechanism, distantly-located gate-actuating mechanisms at opposite sides thereof, each adapted to be actuated by the passing train, and cables con-

nnecting said gate mechanism with the respective gate-actuating mechanisms, the cables being thus in connection with each other, weights suspended at the opposite ends of these connected cables and in balanced relation, one weight being raised and the other lowered in either extreme position of the gate mechanism, lower disconnected weights associated with said suspended upper weights and each adapted to be raised by the respective gate-actuating mechanism as the train passes thereover, with means for connecting each lower weight when raised with its associated upper weight to cause the gravitation or fall of both weights, whereby the gate mechanism is operated in opposite directions as the train passes successively over the two gate-actuating mechanisms; and, in addition to the foregoing, each gate-actuating mechanism comprising a duplicate set of weights and associated instrumentalities reversely arranged and reversely connected by cables to the gate mechanism, considered with respect to the first-named sets of weights and instrumentalities, whereby the gate mechanism is also operated in a reverse manner in opposite directions as the train passes over the gate-actuating mechanisms going in an opposite direction to that first considered.

6. In an automatic train-operated railway-gate, the combination of a gate mechanism, and a gate-actuating mechanism located at a distance therefrom, the same comprising a pair of suspended weights connected by cables with the gate mechanism and in balanced relation, one weight being raised and the other lowered in either extreme position of the gate mechanism, a pair of disconnected weights lower and associated with the respective upper weights, a machinery or instrumentality adapted to be actuated by the passing train and adapted to lift one lower weight when the train travels one way and the other lower weight when the train passes the opposite way, and means whereby each lower weight when raised connects with its associated upper suspended weight to lower the latter by gravity, whereby the gate mechanism is operated to close the gate as the train travels toward the same over the gate-actuating mechanism and operated to open the gate as the train travels away from the same over the same mechanism.

7. In an automatic train-operated railway-gate, the combination of a gate mechanism, and a gate-actuating mechanism located at a distance therefrom, the same comprising a pair of suspended weights connected by cables with the gate mechanism and in balanced relation, one weight being raised and the other lowered in either extreme position of the gate mechanism, a pair of disconnected weights lower and associated with the respective upper weights, a machinery or instrumentality adapted to be actuated in opposite

directions by the passing train, according to the direction of travel of the train, means for lifting one or the other of the lower weights according to the direction of travel and consequent movement of the said machinery or instrumentality, and means whereby each lower weight when lifted connects with its associated upper suspended weight and drags down the latter by gravity.

10. 8. In an automatic train-operated railway-gate, the combination of a gate mechanism, and a gate-actuating mechanism, the latter comprising an instrumentality adapted to be actuated by the passing train, a weight adapted to be lifted thereby, a higher weight suspended from a cable connected with the gate mechanism, and raised during one extreme position of the gate mechanism, and means for connecting said weights when the lower one is lifted, whereby the suspended weight is caused to descend with the lower one, thereby operating the gate mechanism to its other extreme position.

9. In an automatic train-operated railway-gate, the combination of a gate mechanism, and a gate-actuating mechanism, the latter comprising an instrumentality adapted to be actuated by the passing train, a weight adapted to be lifted thereby, a higher weight suspended from a cable connected with the gate mechanism, and raised during one extreme position of the gate mechanism, and hooks or catches on one weight which engage pins or the like on the other when the lower weight is lifted up to the upper one and which disengage or unhook when both weights are down.

10. In an automatic train-operated railway-gate, a gate-actuating mechanism comprising a lever adapted to be moved by the passing train, an inclined guideway, weights slideable thereon, the upper weight being suspended in raised position from a cable connected with the gate in one extreme position thereof, the lower weight adapted to be raised by said lever, and means whereby said weights connect when the lower one is raised, causing the descent of both by gravity and thus operating the gate.

11. In an automatic train-operated railway-gate, the combination of a gate mechanism, and a gate-actuating mechanism, the latter comprising two levers, one of which is

actuated by the train passing in one direction and the other by the train passing in the opposite direction, two inclined guideways, a pair of weights slideable on each way, the upper weights being connected by cables with the gate mechanism and in balanced relation, one upper weight being raised and suspended thereby in one extreme position of the gate mechanism and the other lowered and vice versa for the other extreme position of the gate mechanism, the two levers respectively coacting with the two lower weights to raise them, and means whereby each associated pair of weights connect when both are raised, causing descent by gravity, and disconnected when both are lowered, allowing free ascent of the upper weight.

12. In an automatic train-operated railway-gate, the combination of a gate mechanism, and a gate-actuating mechanism, the latter comprising two levers arranged transversely of the track and working vertically side by side, a medially-fulcrumed rocker arranged longitudinally of the track above said levers and having its arms adapted to bear upon the respective levers and having a medial upright arm adapted to be engaged by the passing train, whereby one lever or the other is actuated according to the direction of travel, two subjacent levers respectively actuated by the first-named levers, oppositely-inclined guideways below the first-named levers, a pair of weights slideable on each guideway, the upper weight being connected by cables to the gate mechanism and in balanced relation, one weight being suspended thereby and the other lowered for one extreme position of the gate mechanism and vice versa for the other extreme position, the lower weights being disconnected and respectively cooperative with the second-named levers and liftable thereby up the inclined guideways, and means whereby each lower weight connects with its associated upper weight when lifted and disconnects when both weights are down.

In testimony whereof I affix my signature in presence of two witnesses.

CHARLES EDWARD FANNING.
